(57) CLAIM

The ornamental design for a table leg, as shown and described.

DESCRIPTION

FIG. 1 is a front perspective view of our new design for a table leg;

FIG. 2 is a top view of the table leg shown in FIG. 1;
FIG. 3 is a bottom view of the table leg shown in FIG. 1;
FIG. 4 is a front view of the table leg shown in FIG. 1;
FIG. 5 is a rear view of the table leg shown in FIG. 1;
FIG. 6 is a left side view of the table leg shown in FIG. 1; and,

FIG. 7 is a right side view of the table leg shown in FIG. 1. The broken lines in the drawings are for illustrative purposes only and form no part of the invention.
